LEDGER PLATE

James R. Sutherland, Minneapolis, Minn., assignor to
Viking Corporation, Minneapolis, Minn.

Filed May 6, 1964, Ser. No. 79,852

Term of patent 14 years

(Cl. D40—1)

FIGURE 1 is a top view of the ledger plate embodying my new design;

FIGURE 2 is a right side elevational view of the new ledger plate with the left side elevational view being a mirror image of the same;

FIGURE 3 is a rear end elevational view of the same;

FIGURE 4 is a front end elevational view of the same; and

FIGURE 5 is a bottom view of the same.

I claim:

The ornamental design for a ledger plate, as shown and described.
